LOCKING MEANS FOR FOLDING
TABLE LEGS

George Peterson, Seattle, Wash.

Application June 5, 1946, Serial No. 674,549

6 Claims. (Cl. 311—87)

1

This invention relates to locking means for folding table legs and an object of this invention is to provide table leg locking means that is simple, inexpensive, strong and durable in construction and highly efficient in operation.

Another object is to provide table leg locking means that is very easy and convenient to operate in unfolding and folding the legs of a table and that is not in the way when the table is in use.

Another object is to provide table leg locking devices that will act as strut means to efficiently brace and hold the table legs when they are in an extended or open position thereby contributing greatly to the stability of the table.

Another object is to provide table leg locking means that will firmly but resiliently hold the table legs in a folded or inoperative position thereby preventing the folded table legs from falling to an open position when the table is handled but allowing the folded table legs to be very quickly and easily moved to an open position manually.

Another object is to provide a table structure of a type well adapted for use in the construction of small tables such as card tables.

Another object is to provide table leg locking means in which two pivotally mounted strut members are used for holding two pairs of table legs in either a folded or an open position and in which a pressure bar supported by a centrally positioned spring is used to yieldingly hold the strut members in engagement with cross bars that connect the two table legs of each pair.

In the drawings Figure 1 is a longitudinal sectional view of a table structure having legs and leg locking means constructed in accordance with this invention and showing the legs in a folded position.

Fig. 2 is a bottom plan view of the same looking in the direction of broken line 2—2 of Fig. 1.

Fig. 3 is a longitudinal sectional view of said table showing the legs locked in an open or operative position, parts of the legs being broken away.

Fig. 4 is a fragmentary sectional view showing a modified form of the invention.

Like reference numerals designate like parts throughout the several views.

Referring to the drawings, 5 designates a table top having two transverse reinforcing bars 6 and 7 rigidly secured to its bottom side adjacent two opposite edges or ends thereof. Two pairs of swingingly mounted table legs 8 and 9 of duplicate construction are provided. The two legs 8 of one pair have their upper end portions rigidly

secured to a cross piece 10. The two legs 9 of the other pair have their upper end portions rigidly secured to another cross piece 11. The two table legs 8 are transversely offset relative to the two table legs 9 so that said table legs will fold alongside of each other without interference. This can be done by positioning the two table legs 8 further apart than the two table legs 9.

The cross pieces 10 and 11 are positioned adjacent the respective reinforcing bars 6 and 7 and are connected by hinges 12 with the table top 5. The hinges 12 are positioned far enough away from the reinforcing bars 6 and 7 so that when the table legs are in the open position, shown in Fig. 3, the cross pieces 10 and 11 will rest against the reinforcing bars 6 and 7 respectively and be braced and supported thereby against further outward swinging movement of the legs 8 and 9. The bars 6 and 7 thus function as stop members.

Means for positively holding the table legs in an open or extended position and for resiliently holding said table legs in a folded position is provided. This means comprises two strut members 13 and 14 connected by hinges 15 with a centrally positioned block 16 that is rigidly secured to the bottom side of the table.

A bolt 17 is rigidly secured to the block 16 and projects downwardly therefrom. A pressure bar 18 has its medial portion slidably mounted on the bolt 17. The pressure bar 18 extends in opposite directions from the bolt 17 underneath the strut members 13 and 14 and the end portions of said pressure bar engage with and press against the strut members 13 and 14. A compression spring 19 is provided on the bolt 17 and adjustable nut means 20 is provided on the bolt 17 to support the spring 19. Preferably a washer 21 is provided at each end of the spring 19. Also preferably the end of the bolt 17 is upset or mutilated to prevent complete removal of the nut means 20.

The end portions of the pressure bar 18 that contact the strut members 13 and 14 preferably are beveled to conform in a general way to the incline of the strut members 13 and 14. These end portions are also provided with longitudinal slots 22 that fit over stud pins 23 which are rigidly secured to the strut members 13 and 14. The pins 23 prevent sidewise displacement of the pressure bar 18 relative to the strut members 13 and 14.

The lowermost inner corners of the cross pieces 10 and 11 have notches 24 therein for the reception of the ends of the strut members 13 and

14 when the legs 8 and 9 are in the operative position shown in Fig. 3.

Fig. 4 shows pressure bar means of modified form which makes possible the use of a shorter stud bolt thereby reducing the over all thickness of the table when folded and making the stud bolt short enough to substantially eliminate the danger of damaging walls and other furniture through contact with this stud bolt.

The structure shown in Fig. 4 uses a metal pressure bar 24 having an arched medial portion 35. The arched medial portion 35 extends between the hinged ends of two strut members 26 and 27 which are similar to the strut members 13 and 14 except that they have grooves 28 to receive protruding portions 29 on the outer end portions of the strut members 26 and 27.

The grooves 28 and protruding portions 29 replace the slots 22 and pins 23 of Figs. 1 to 3. A relatively short stud bolt 30 rigid with the table 5 protrudes through the pressure bar 24 and into the arched portion 35 thereof and has a compression spring 31 thereon to yieldingly press the outer end portions of the pressure bar against the strut members 26 and 27. In this construction the stud bolt 30 and spring 31 are shielded and protected so that they are not liable to come in contact with walls, floors and pieces of furniture when the table is folded. The structure shown in Fig. 4 operates in the same manner as the structure shown in Figs. 1 to 3.

When the legs of this table are folded, as shown in Fig. 1, they will lie close to the table 5 and alongside of each other and the strut members 13 and 14 will yieldingly engage with the cross pieces 10 and 11 with sufficient force to retain these cross pieces and the legs 8 and 9 in a folded position. To set up the table the legs 8 and 9 are quickly and easily swung downwardly into positions perpendicular to the table. In these positions the cross pieces 10 and 11 rest firmly against the reinforcing bars 6 and 7 and the end portions of the strut members 13 and 14 drop into the notches 24 and lock the table legs against inward swinging movement. Obviously these table legs will be firmly locked against inward swinging movement as long as the ends of the strut members are engaged within the notches 24 but can be folded inwardly when the end portions of said strut members are lifted out of the notches 24.

The springs 19 and 31 can be of any desired strength and the pressure of these springs can be adjusted by adjusting the nut means that supports them and the useful life of these springs will ordinarily be greater than the life of the table. The springs 20 and 31 are usually adjusted to yieldingly hold the table legs in a folded position by enough pressure so that said table legs can easily be opened out manually. However, if the nuts are tightened sufficiently against the springs the table legs can be positively locked in a folded position. To facilitate quick and easy adjustment of the nuts that hold the springs 20 and 31 I may use wing nuts for this purpose.

Obviously changes in this invention may be made within the scope and spirit of the following claims.

I claim:

1. A table structure comprising a table top; two pairs of table legs pivotally connected with said table top in spaced apart relation; a cross piece rigidly connecting the two legs of each pair; a stud bolt rigidly secured to said table top between said two pairs of table legs and extending downwardly therefrom; two strut members

hinged to said table top adjacent said stud bolt and extending outwardly therefrom and engaging the respective cross pieces of said two pairs of table legs to hold said table legs in either a folded or an open position; a pressure bar having its medial portion slidably mounted on said bolt and its end portions resting against said strut members at equal distances from said bolt; and a spring on said bolt yieldingly urging said pressure bar against said strut members providing equal pressure on each of said strut members.

2. A table structure comprising a table top; two cross pieces hinged to the under side of said table top near opposite sides thereof; two table legs rigid with each cross piece; a stud bolt rigidly secured to the medial portion of said table top and extending downwardly therefrom; two strut members hinged to said table top adjacent said stud bolt and extending toward and over said cross pieces, said cross pieces having notches adapted to receive the end portions of the strut members when the cross pieces rest against said reinforcing bars; a pressure bar having its medial portion slidably mounted on said bolt and its end portions resting against said strut members at equal distances from said bolt; and a spring on said bolt yieldingly urging said pressure bar against said strut members providing equal pressure on each of said strut members.

3. A table structure comprising a table top; two cross pieces positioned below said table top and hinged thereto near opposite sides of said table top; table legs rigid with each cross piece and movable between positions substantially perpendicular to and substantially parallel with said table top; two strut members hinged to the medial portion of said table top in spaced apart relation and having their outer end portions positioned in engagement with said cross pieces to hold the leg members in either a folded or an open position; a pressure bar having its two end portions positioned on said strut members and having an arched medial portion positioned between the hinged end portions of said strut members and in close proximity to the bottom surface of said table top; a stud bolt rigid with said table top and extending downwardly therefrom through said arched portion of said pressure bar; and a compression spring on said stud bolt urging said pressure bar against said strut members, said stud bolt and spring being shielded within the arched portion of said pressure bar.

4. A table structure comprising a table top; two reinforcing bars rigidly secured to the under side of said table top and extending across the same near opposite sides thereof; two cross pieces hinged to said table top inwardly from said bars and arranged to swing outwardly against said bars; two table legs rigid with each cross piece; a stud bolt rigidly secured to the medial portion of said table top and extending downwardly therefrom; two strut members hinged to said table top adjacent said stud bolt and extending toward and over said cross pieces, said cross pieces having notches adapted to receive the end portions of the strut members when the cross pieces rest against said reinforcing bars; a pressure bar having its medial portion slidably mounted on said bolt and its end portions resting against said strut members at equal distances from said bolt; and a spring on said bolt yieldingly urging said pressure bar against said strut members providing equal pressure on each of said strut members.

5. A table structure comprising a table top; two reinforcing bars rigidly secured to the under

side of said table top and extending across the same near opposite sides thereof; two cross pieces hinged to said table top inwardly from said reinforcing bars and arranged to swing outwardly against said reinforcing bars; two table legs rigid with each cross piece; a block secured to the under side of said table medially thereof; a stud bolt rigid with said block and extending downwardly therefrom; two strut members hinged to said block and extending in opposite directions therefrom and having their outer end portions positioned on the respective cross pieces; notches in the innermost lower corners of said cross pieces positioned to receive the outer end portions of said strut members when said cross pieces and the legs connected therewith are perpendicular to said table top; a pressure bar having its medial portion slidably mounted on said bolt and having its end portions positioned in engagement with said strut members; and a spring on said bolt yieldingly urging said pressure bar toward said strut members.

6. A table structure comprising a table top; two reinforcing bars secured to the under side of said table top and extending across the same near opposite sides thereof; two cross pieces hinged to said table top inwardly from said reinforcing bars and arranged to open against said reinforcing bars; two table legs rigid with each cross piece, the legs carried by each cross piece being transversely offset relative to the

legs carried by the other cross piece; a block secured to the under side of said table medially thereof; a stud bolt rigid with said block and extending downwardly therefrom; two strut members hinged to said block and extending in opposite directions therefrom and having their outer end portions positioned on the respective cross pieces; notches in the innermost lower corners of said cross pieces positioned to receive the outer end portions of said strut members when said cross pieces and the legs connected therewith are perpendicular to said table top; a pressure bar carried by said bolt and having its end portions positioned in engagement with said strut members; means preventing transverse displacement of said pressure bar and said strut members; a spring on said bolt yieldingly urging said pressure bar toward said strut members; and adjustable nut means on said bolt supporting said spring.
